UNITED STATES PATENT OFFICE.

GEORGE F. EARHART, OF WINTERSET, IOWA.

BRICK-DIE.

SPECIFICATION forming part of Letters Patent No. 268,879, dated December 12, 1882.

Application filed August 1, 1881. (No model.)

To all whom it may concern:

Be it known that I, GEORGE F. EARHART, a citizen of the United States, residing at Winterset, in the county of Madison and State of Iowa, have invented certain new and useful Improvements in Brick-Dies; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to brick molds or dies used in brick-machines; and it consists in certain improvements in the construction of the mold or die, as hereinafter shown and described.

In the accompanying drawings, Figure 1 represents a plan view of the improved mold. Fig. 2 is a side view of the same, a part being removed. Fig. 3 is a bottom plan, and Fig. 4 is a horizontal section.

The mold is formed of the parts A and A', fastened together, the part A' being circular and projecting like a flange for the purpose of attaching the mold and fitting it in the chamber of a brick-machine. The opening a in the part A' is rounded at the corners, as shown, and has beveled sides and ends, so that it is gradually reduced toward the opening through the part A, the latter opening being also reduced gradually, and both openings forming a passage for the volume or bar of clay through the mold.

It will be seen that the passage or opening through section A is rectangular, so that recesses are formed at the corners under the inner rounded corners of the section A'. To cover these recesses, so that the forming-passage through the mold shall be even and smooth, and also to form the chambers or water-passages c at the corners, the shields B are pro-

vided, the same being of sheet metal, and secured in place at each corner of the section A. 45 The said shields, at their upper edges, conform to and are even with the rounded corners of the opening in section A', and, extending downward, are gradually brought to a rectangular form at their lower edges to set in the corners 50 of the passage through section A. This construction prevents the cracking of the clay at the corners as it passes through the forming-section A' into the finishing section A, the passage for clay through the mold being gradually brought from a rounded form to a rectangular form at or near the point of exit.

The apertures d through the casing communicate with the chambers or water-passages c, and are intended to receive tubes through 60 which water passes into said passages, and through the same wetting the clay at the corners and leaving the bar dry at the center. The bar of clay, made the length and breadth of a brick, issues out on a table, like a tile-table, and is there cut by means of wires attached to a frame to any desired thickness. The fixed pins or rods b, extending into the mold to make holes in the brick, are so placed as to leave the central part of the bar of clay 70 solid, so that it is less liable to crack in drying and burning.

I claim—

In a brick-mold, the section A', having the passage for clay with rounded corners, in combination with the section A, having the passage with rectangular corners to form passages c, the shields B, and apertures d, the parts being constructed as shown, for the purposes set forth.

In testimony whereof I affix my signature in presence of two witnesses.

GEORGE F. EARHART.
